UNITED STATES PATENT OFFICE.

FREDERICK WESTERMAN, OF CHICAGO, ILLINOIS.

DEPOSITING-MACHINE.

1,121,431.

Specification of Letters Patent. Patented Dec. 15, 1914.

Application filed December 20, 1913. Serial No. 807,851.

To all whom it may concern:

Be it known that I, FREDERICK WESTERMAN, a citizen of the United States, residing in Chicago, county of Cook, and State of Illinois, have invented certain new and useful Improvements in Depositing-Machines, of which I do declare the following to be a full, clear, and exact description, reference being had to the accompanying drawings, forming a part of this specification.

The present invention has relation to that class of depositing machines more particularly designed for depositing marshmallow or other confection upon the upper surface of cakes that are fed in successive rows beneath the depositing mechanism.

More particularly, my invention is designed as an improvement upon the depositing machine set forth in an application for Letters Patent filed by me in the United States Patent Office May 29, 1911, Serial No. 630,268.

The present invention consists in the various features of improvement hereinafter described, illustrated in the accompanying drawings and particularly pointed out in the claims at the end of this specification.

Figure 1 is a view in side elevation of a depositing machine (portions being omitted) embodying my invention. Fig. 2 is a view in vertical longitudinal section through the machine. Fig. 3 is a view similar to Fig. 1 but taken from the opposite side of the machine. Fig. 3^a is a top plan view of the gear mechanism shown at one end of the plunger carriers in Fig. 3. Fig. 4 is a view in horizontal section on line 4—4 of Fig. 3. Fig. 5 is a view in vertical cross section on line 5—5 of Fig. 6 enlarged. Fig. 6 is a view in vertical longitudinal section on line 6—6 of Fig. 5. Fig. 7 is a view in vertical longitudinal section on line 7—7 of Fig. 5 (parts being broken away). Fig. 8 is a view in horizontal longitudinal section on line 8—8 of Fig. 6, looking upward, parts being broken away. Fig. 8^a is a detail sectional view upon an enlarged scale in a changed position of one of the nipples of a depositing mechanism and associated parts. Fig. 9 is a view in vertical transverse section on line 9—9 of Figs. 1 and 10. Fig. 10 is a view in vertical longitudinal section on line 10—10 of Fig. 9. Fig. 11 is a view in longitudinal section on line 11—11 of Fig. 10 (parts being broken

away). Fig. 12 is a view in horizontal section on line 12—12 of Fig. 10.

While I have illustrated in the accompanying drawings what I regard as the preferred embodiment of my invention, I wish it understood that the details of construction above set out may be varied without departing from the spirit of the invention and that features of the invention may be employed without its adoption as an entirety.

The main frame of my improved machine comprises side portions 1 that are suitably connected together by transverse bolts at convenient points. At the front end of the main frame is mounted the mechanism whereby the cakes that are to receive the coating of confection will be successively advanced in orderly rows beneath the mechanism whereby the discharge of confection upon the upper surfaces of the cakes will be effected. The mechanism for advancing the cakes to receive the deposits of confection and the mechanism for carrying off the cakes will first be described.

Across the front of the main frame and mounted in suitable bearings thereon extends a shaft 2. Upon this shaft 2 adjacent its ends are pivotally mounted the hubs 3 at the lower ends of the depending portions 4 of the side frames or castings 5, to which are bolted the vertical side plates 6, between which are arranged the stationary and movable steps whereby the cakes are successively advanced onto a carrier plate, as will presently appear. Between the upper portions of the side plates 6 extends a top step or table 7 and extending downwardly and forwardly from this top step or table 7, and with intermediate spaces between them, are arranged stationary steps 8. The ends of these stationary steps are suitably connected to side plates 6 and preferably the front edge of each of the steps 8 is formed with a downward and outward inclination. Beyond the front edge of each of the steps 8 projects a knife edge metal plate 9 that extends from end to end of the step and is flush with the upper surface of the step. Between the several stationary steps are arranged the movable steps 10 (see Fig. 2) that are mounted in manner free to reciprocate back and forth in the spaces between the stationary steps. As shown, these movable steps comprise open frames the side bars 11 of which are bolted together with spacing 110

washers between them and are bolted also to the reciprocating cross bar or frame 12. This cross bar or frame 12 is shown as comprising an angular metal plate that extends 5 between the side plates 6 and to the angular plate 12 are attached the ends of the metal side bars of the steps. The back of this plate 12 has bolted at its center a bracket 13. To the inner face of each of the side plates 10 6 and between such side plates and the corresponding end of the plate 12 is bolted a casting 15 having an inwardly projecting ledge 16 (see Figs. 1 and 2) upon which rest, in a manner free to slide, the ends of a bar 15 17 that extends from side to side beneath the side bars 11 of one of the movable steps, the ends of this bar 17 being bolted to side bars 11 of one of the steps. The purpose of this bar 17 is to aid in supporting the 20 group of movable steps in a manner free to reciprocate back and forth. Preferably, metal shoes 17^a are attached to the ends of the cross bar 17, these shoes sliding upon the ledges 16 of the brackets 15 and saving the 25 ends of the bar 17 from wear.

To the bracket 13 is pivotally connected the inner end of a link 20, the outer end of which link is pivotally connected by a bolt 21 to a depending link 22 that is pivoted as 30 at 23 to a bracket bolted to the underside of the stationary step or table 7. The bolt 21 passes through the slotted upper end of a rocking arm 24 that is pivotally mounted on the shaft 2 (see Figs. 2 and 4). Through 35 the lower slotted end of the rocking arm 24 passes a bolt 25 to which is connected the upper end of an eccentric rod 26 that is adjustably connected to the yoke 27 (see Figs. 2 and 4) that fits around an eccentric 40 28 on a shaft 29 that is journaled in suitable bearings in the main frame of the machine. This shaft 29 is connected by gear wheels 31 and 32 to the drive shaft 34 that is journaled in the main frame of the machine, one end of this drive shaft 34 extending 45 outside the main frame and being provided with a suitable drive pulley 35 (see Fig. 4). From the description thus given, it will be seen that, when the drive shaft 34 is rotated, motion will be imparted therefrom to the shaft 29 and through the eccentric 50 28, eccentric yoke 27 and pitman 26, a rocking movement will be imparted to the rocking arm 24; and, as the upper end of 55 this rocking arm is connected by the link 20 and bracket 13 to the angle bar 12 (see Fig. 2), a corresponding reciprocating movement will be imparted to the series of movable steps 10.

60 Beneath the lowermost stationary step 8 is mounted a supplemental movable step 10^a, the side arms 11^a of which are connected at their outer ends to a cross bar 11^b (see Fig. 2), to the under side of which is bolted a 65 bracket 11^c that is pivotally and adjustably

connected by a link 11^d to the lower end of the link 22. Hence, it will be seen that when movement is imparted to the rocking arm 24 to reciprocate the movable steps in manner before described, a corresponding 70 reciprocation will be imparted through the link 22 and the rod 11^d to the supplemental movable step 10^a; but because of the connection of the rod 11^d to the extreme lower end of the link 22, a considerably longer throw 75 will be imparted to the lowermost supplemental step 10^a than is given to the movable steps 10. By reference to Fig. 2 of the drawings, it will be seen that the front edge 80 of each of the movable steps 10 is inclined downwardly and outwardly and a thin metal plate 10^e is mounted upon the side bars of each of the movable steps and projects over the front edge thereof. The purpose of this arrangement will hereinafter more fully appear. 85

To the inner portions of the side frames 5 (see Figs. 1 and 2) are bolted, as at 5^a, the forward ends of side bars 40 (see Fig. 2) that carry the table 41 over which passes 90 the upper member of a carrier belt 46 that serves to carry off the cakes after the confection has been deposited thereon. The inner ends of the side bars 40 of the table 41 are connected to the outer ends of brackets 40^a pivotally connected to a cross shaft 42 and to this cross shaft are also pivotally connected the inner ends of brackets 43 to which are bolted the side angle bars 44 of the rear member 45 of the belt-supporting table. 95 Shaft 42, that pivotally connects the sections 41 and 45 of the belt carrying table, carries a roller (see Fig. 2) over which passes the upper member of the belt 46, while the lower member of this belt passes beneath the shaft 100 42 and over a roller on the shaft 47 that is journaled in the end brackets 43 of the table section 45. In the drawings I have shown a portion only of the table section 45 and means adjacent thereto for sustaining the 105 carrier belt 46, as this part of the present machine is the same as in my application No. 630,268, filed in the Patent Office May 29, 1911, hereinbefore referred to, and need not, therefore, be shown or described. The 110 inner portions of the table sections 41 and 45 are adapted to be lifted, with the carrier belt 46 thereon, by means of the rods 48 (see Figs. 1 and 2), as in the machine set forth in my above mentioned application, the upper ends of these rods being pivotally connected as at 48^a to downwardly projecting lugs on the brackets 40^a to which the sidebars 40 are attached, while the lower ends of the rods 48 are provided with adjustable trunnions 49 that are mounted in the rock arms 50 fixed to a rock shaft 51. The rock shaft 51 has connected thereto a yoke-shaped rock arm 52 (see Figs. 2 and 4) that carries at its free end a roller 52^a which bears against the 115 120 125 130 135

face of a cam 54 that is mounted on the cam shaft 29, this cam being adjustably bolted (see Fig. 2) to a disk that is fixed to the shaft 29. Hence, it will be seen that as the 5 cam shaft 29 is rotated, a rocking movement will be imparted to the rock shaft 51 and, through the rock arms 52 and 50 and vertical rods 48, the table sections 41 and 45, with the carrier belt 46 thereon, will be raised and 10 lowered in order to bring the rows of cakes beneath the discharge nipples or spouts of the depositing mechanism to be presently described. A step - by - step motion is imparted to the carrier belt 46 and by mechanism like that shown in my before-mentioned application No. 630,268.

On the end of a shaft 60 that is journaled in suitable bearings adjacent the front of the machine (see Figs. 1 and 2) is mounted 20 a rocking arm 61, the upper end of which carries a pawl 62 that engages with a ratchet wheel 63 keyed to the shaft. This shaft 60 carries a roller 64 over which the carrier belt 46 passes. The lower end of the rock arm 25 61 is adjustably connected by a rod 66 to an arm 67 pivotally mounted on a stud 68 projecting from one of the sides of the main frame. The lower end of this rock arm 67 is connected by a rod 69 to a rock arm 70 30 mounted on the shaft 71 journaled in bearings at the rear end of the main frame. To the lower end of this rock arm 70 is adjustably connected the rear end of a rod 72, the forward end of which is pivoted to a rock 35 arm 73 that has its upper end pivoted to a stud 74 projecting from the main frame, and this rock arm 73 carries a roller 73^a that bears against the periphery of a cam wheel 75 mounted on the cam shaft 29. The shaft 40 71 carries a roller 77 around which passes the carrier belt 78, the function of this belt being to carry the trays into which the coated cakes will be delivered, but, inasmuch as this carrier belt and the mechanism for 45 operating it are substantially the same as in my hereinbefore mentioned application, No. 630,268, a description of such mechanism is not deemed necessary. When rotation is imparted to the cam shaft 29, the cam 50 75 will swing the rocking arm 73 and through this rocking arm and through the rod 72 the rocking arm 70, the rod 69, the rocking arm 67, the rod 66, the rocking arm 61 and pawl 62, a step-by-step rotation will 55 be imparted to the ratchet wheel 63 and the roller 64 around which the carrier belt 46 passes.

In the present construction, as in the machine in my before mentioned application 60 No. 630,268, the cakes, upon the upper surfaces of which confection is to be deposited, will be placed indiscriminately upon the steps above the forward end of the carrier belt, and will be moved downward 65 and advanced toward the carrier belt 46 by

the reciprocating movement of the movable steps. The beveled edges of the steps aid in preventing the upturning of the cakes as they are pushed from step to step, and the projecting edges of the plates 9 on the stationary steps 8 coöperate to this end. So, also, the front edges of the plates 10^c, projecting beyond the front edges of the movable steps 10, aid in preventing the up-tipping of the cakes as they are pushed from 70 the stationary steps. When the cakes have been delivered on to the carrier belt 46, the supplemental step 10^a advances the cakes in transverse rows beneath the confection depositing mechanism and, inasmuch as the 75 throw of this supplemental step 10^a can be adjusted by reason of its adjustable connection with the link 22, (see Fig. 2), the rows of cakes can be brought centrally beneath the depositing mechanism, regardless of the 80 diameters of the cakes.

The mechanism whereby the depositing of the confection is effected upon the tops of the transverse rows of cakes, as such rows are advanced successively step by step, will 90

In the present form of my invention, the depositing mechanism is shown as adapted to deposit upon the cakes three kinds of confection, and as this depositing mechanism is constructed it will place upon the top of each cake a charge of one kind of confection, such, for example, as marshmallow, covered by another kind of confection, such, for example, as chocolate, and 95 will embed in the center of the previously deposited confections a third confection such, for example, as jelly. The mechanism for depositing the third kind of confection, such as jelly, may be omitted, if desired. 100 So, also, features of the mechanism employed for depositing the other two kinds of confection may be employed without 105 adopting such mechanism as an entirety.

Upon raised portions 1^a and 1^b of the side 110 frames 1 of the machine, (see Figs. 1 and 2) is secured the casting 100 that extends from side to side of the machine. This casting 100 is formed with two cylindrical openings 115 extending from end to end thereof (see Figs. 5 and 6). Within the cylindrical openings of the casting 100 are mounted the cylindrical plunger carriers 101 and 102. The plunger carrier 101 extends beneath and is adapted to close the bottom opening 120 of a chamber 103 for marshmallow or like confection, while the plunger carrier 102 extends beneath the bottom of a similar chamber or receptacle 104 adapted to contain chocolate or other confections that will 125 cover the marshmallow when the latter is deposited upon the cakes. The cylindrical plunger carriers 101 and 102 are identical in construction. Each of these plunger carriers is shown as comprising two half seg- 130

ments (see Fig. 6) that will be bolted together, these segments being formed as skeleton or chambered castings to decrease their weight. That part of the plunger carrier 101 beneath the bottom opening in the receptacle 103 is formed with an open space 106, along each side of which extends a plate 107. Each of the plates 107 is attached by screws to the plunger carrier 101, as shown in Fig. 6. The end portion of the plunger carrier 101, at each side of the central portion which lies beneath the receptacle 103, is of somewhat smaller diameter than the central portion of the plunger carrier (see Fig. 5) and, through these end portions of the plunger carrier 101 extend the reduced end portions of the plates 107. Around the peripheries of the end portions of the plunger carrier 101 are fitted the bearing sleeves 110 and 111 (see Fig. 5) that fill the space between the end portions of the plunger carrier and the cylindrical openings in the casting 100. By reference to Fig. 5, it will be seen that the sleeve 110 is formed adjacent its end with a peripheral groove adapted to receive the end of a set-screw 112 that securely holds the sleeve in place against longitudinal movement, and this sleeve 110 is also formed with a peripheral groove 113 adjacent its inner end into which oil will be admitted by a passage 113^a from an oil receptacle 114 (see Fig. 7) that is formed between the cylindrical portions of the casting 100. Preferably, a friction block 115 bears upon the surface of the cylindrical sleeve 110. This friction block 115 (see Fig. 5) is held within a chamber formed within the end portion of the casting 100, and the block is forced downward by a coil spring that encircles its shank (see Fig. 7). The shank of the block passes through a screw threaded cap that closes the top of the chamber in which the friction block is contained. The cylindrical sleeve 111 at the opposite side of the machine has its periphery grooved for the same purpose as the sleeve 110, last described, and, preferably, a friction block is arranged to bear upon the surface of this sleeve, as shown in Fig. 5 of the drawings.

Through the plunger carriers 101 and 102 pass the squared bars 120 and 121. These bars 120 and 121 have mounted thereon respectively the plungers 122 and 123 adapted to reciprocate within the longitudinal spaces 106 of the plunger carriers and between the plates 107. As shown, each of these plungers 122 and 123 consists of plates or bars extending upon opposite sides of the longitudinal bars 120 and 121, respectively, these plunger plates or bars being connected together by side plates 126 that fit snugly, but in manner free to slide, against the face of the plates 107.

65 By reference more particularly to Figs. 3,

3^a, 5 and 7 of the drawings, it will be seen that upon the cylindrical sleeve 110 at the end of the plunger carrier beneath the marshmallow receptacle 103 is fixed an annular gear wheel 130, and, similarly, upon the cylindrical sleeve at the corresponding end of the plunger carrier beneath the chocolate receptacle 104 is fixed an annular gear wheel 131. These gear wheels 130 and 131 do not intermesh (as they might appear to do from Figs. 3 and 7), but are arranged in different vertical planes, as shown in Figs. 3^a and 5. The gear wheel 130 meshes with a mutilated gear wheel 133 that is formed with segmental slots 134 through which pass bolts 135 whereby the gear wheel 133 is connected to sprocket wheel 136 that is journaled upon a stud axle 137 projecting outwardly from the main frame. The stud axle 137 is preferably adjustably mounted within a slot 138 of the main frame (see Fig. 2). By means of the bolt and slot connection, the position of the gear wheel can be accurately adjusted. The mutilated gear wheel 133 is shown as provided with fourteen teeth and, when these teeth pass from engagement with the gear wheel 130, the gear wheel 130 and the cylindrical plunger carrier, to which this gear wheel is connected, will remain stationary in the position shown in Fig. 6 of the drawings until the plunger 122 has completed its stroke in manner to be hereinafter described. Around the sprocket wheel 136 passes a sprocket chain 139 that passes around a sprocket wheel 140 (see Figs. 2 and 3) journaled on a stud axle 141 that is adjustably mounted in a slot 142 of the main frame. To this sprocket wheel 140 is bolted a gear wheel 144 that meshes with a gear wheel 145 on the shaft 146 (see Figs. 2, 3 and 4). The gear wheel 145 meshes with a gear wheel 150 on the end of a shaft 151 journaled in the main frame. The gear wheel 150 meshes with a gear wheel 153 that is bolted to a sprocket wheel 154 journaled on a stud axle 155 adjustably mounted in a slot 156 of the main frame (see Fig. 2). Around the sprocket wheel 154 passes a chain 157 that passes around a sprocket wheel 158 mounted upon a stud axle 159 that is adjustably bolted within a slot 160 of the main frame, (see Fig. 2). To the sprocket wheel 158 is attached the mutilated gear wheel 165, this gear wheel being similar to and having a like number of teeth as the gear wheel 133, and this gear wheel 165 is adjustably bolted by a slot and bolt connection to the sprocket wheel 158, as clearly shown in Fig. 3. The gear wheel 165 meshes with the annular gear wheel 131 that is mounted upon the sleeve 110 (see Fig. 7), on the end of the cylindrical plunger carrier beneath the chocolate receptacle 104. Inasmuch as the construction of the plunger carrier beneath the chocolate receptacle 104 and the parts at the ends

thereof is the same as the construction of the plunger carrier and corresponding parts beneath the marshmallow receptacle 103 (which latter are clearly illustrated in Figs. 5 and 7 of the drawings), I have not deemed it necessary to further illustrate the plunger carrier beneath the chocolate receptacle 104. Upon the shaft 146 (see Fig. 1) is mounted a gear wheel 170 (see Figs. 1 and 4) that meshes with a pinion 171 which in turn meshes with a pinion 172, these pinions being journaled upon stud axles 171^a—172^a bolted to the main frame. The pinion 172 meshes with the gear wheel 31 that is keyed to the 10 cam shaft 29, driven by the pinion 32 on the drive shaft 34. Through the train of gear mechanism last described, it will be seen that the rotation of the cylindrical plunger carriers 101 and 102 will be effected. It will be 15 seen also, that inasmuch as the annular gear wheels 133 and 165, that drive these cylindrical plunger carriers are mutilated, the rotation of the plunger carriers 101 and 102 will be temporarily arrested and, while so 20 arrested, the plungers will be caused to operate in manner to be presently described.

The mechanism coöperating with the plungers 122 and 123 to effect the deposits of the marshmallow and chocolate confec-
30 tions upon the tops of the cakes will next be described.

Upon the ends of the plunger bar 120, beneath the marshmallow receptacle 103, are placed the sleeves 120^a to which are pivotally connected the upper ends of the plunger bars 200 and 201, respectively. The lower end of the drive bar 200 is pivotally connected to an eccentric wrist pin 204 that is mounted upon a block 205 adjustably connected to the outer face of the gear wheel 145. As shown in Figs. 3 and 4, the outer face of the gear wheel 145 is formed with parallel flanges 206 having beveled inner faces to form a dovetailed groove to receive the wrist pin block 205. Above and below these flanges are mounted the plates 207 through which passes the through bolt 208 that also passes through the wrist pin block and, by means of this bolt, the adjustment 50 of the wrist pin block can be effected. The plunger actuating bar 201 (see Figs. 1, 4 and 5) at the opposite side of the machine from the bar 200 has its lower end pivotally connected to a wrist pin 210 that projects from a block adjustably mounted on a disk 211 keyed to the end of the shaft 146. The adjustment of the wrist pin is similar to the adjustment of the wrist pin 204 hereinbefore described. Hence, when the plunger 60 actuating bars 200 and 201 are reciprocated, they impart a corresponding reciprocating movement to the plunger 120 beneath the marshmallow receptacle 103. To the opposite ends of the plunger carrier bar 121, beneath the chocolate receptacle 104, are pivot- 65

ally connected the upper ends of the plunger actuating bars 200^a and 201^a, these bars being similar in construction to the plunger actuating bars 200 and 201 last described. The lower end of the actuating bar 200^a is pivotally connected with a wrist pin eccentrically connected to the outer face of the gear wheel 150 on the end of the shaft 151, and, similarly, the lower end of the plunger actuating bar 201^a is adjustably connected to an eccentric wrist pin at the opposite end of the shaft 151, through the medium of a collar keyed to said shaft. The means for adjustably connecting the ends of the plunger actuating bars 200^a and 201^a to the ends of the shaft 151 is similar to the means employed for connecting the plunger actuating bars 200 and 201 to the outer ends of the shaft 146, and, therefore, need not be more fully described.

Beneath the central portion of the casting 100 (see Figs. 5, 6, 7 and 8) extends a chambered casting 220, the longitudinal edges of which are preferably beveled to form a dovetail engagement with a flange 100^a at 90 the bottom of the casting 100, and a corresponding beveled bar 221 formed at the inner side of an adjustable plate or casting 222. By reference to Figs. 6 and 8, it will be seen that this plate or casting 222 is 95 formed with slots 223 through which pass the blocks 224, the expanded heads of which lie beneath the plate or casting 222 and hold the same in place. The adjustment of the plate or casting 222 is effected by means of 100 clamping thumb screws 225 and set-screws 226 extending along its flanged edge, as clearly shown in Figs. 6 and 8. Above the chambered casting 220 extends a cover-plate 230 and through this cover-plate 230 are 105 formed openings 231 and 232 that are arranged upon the opposite side of a central wall or diaphragm 233 at the bottom of the casting 100 (see Fig. 6). The openings 231 communicate with the space 234 that leads 110 to the cylindrical opening in which the plunger carrier 101, beneath the marshmallow receptacle 103, is mounted. Similarly, the openings 232 in the cover-plate 230 communicate with the space 236 that leads into 115 the cylindrical opening in which the plunger carrier 102 is mounted.

120 Into each of the openings 231 is fitted the upper end of a delivery pipe 240. The lower end of this delivery pipe 240 (see Figs. 6 and 8^a) extends partially through an annular nipple 241 that has an inwardly turned, annular flange 242, the interior diameter of which flange corresponds approximately to the peripheral diameter of the delivery pipe 240. Around each delivery pipe 240 fits a cylindrical valve sleeve 244 having trunnion pins 245 projecting from its sides (see Fig. 8). Each of these cylindrical valve sleeves is reciprocated vertically by the arms of a 130

valve shifter 247 that is fixed to a rock shaft 248. By reference to Figs. 6 and 8, it will be seen that the arms of the valve shifter set within the chambers of the casting 220 and 5 the arms are spaced at proper distances apart on the shaft by rectangular sleeves 248^a. The purpose of the tubular cut-off valves 244 is to accurately check the passage of chocolate which will flow through the an- 10 nular space between the nipple 241 and the delivery pipe 240, while the marshmallow is flowing through the delivery pipe 240. While the marshmallow is flowing through each of the delivery pipes 240, the chocolate 15 will be flowing through the annular space around such pipes, so that the deposit of marshmallow, as it is delivered to the top of a cake, will be coated with the chocolate, as will presently more fully appear.

20 The operation of the valve shifters 247 is effected by the mechanism next to be described: On the outer end of the rock shaft 248 (see Figs. 1, 4, 5 and 8) is fixed an arm 250, the free end of which is pivotally connected to the upper end of a rod 251 that passes downward through a guide flange or bracket 252 at one side of the main frame (see Fig. 1) and has its lower end pivotally connected to an arm 253. This arm 253 has 25 one end pivotally connected to a stud 254 (see Fig. 4) extending inwardly from one side of the main frame, and its free end carries a roller 255 that bears upon the periphery of a cam wheel 256 that is mounted upon 30 the shaft 146. A coil spring 258 encircles the lower portion of the rod 251, forcing said rod downward and thereby holding the roller at the end of the arm 253 in engagement with the cam-wheel 256 and causing 35 the rod 251 to move the tubular valves 244 (see Figs. 6 and 8^a) to closed position. From end to end of the central portion of the casting 100 (see Figs. 1, 2, 6, 7 and 8) are formed dovetailed channels or chambers 40 within which are mounted the slide valves 260 and 261. By reference more particularly to the right-hand side of Fig. 8, it will be seen that each of these slide valves 260 and 261 is formed with a series of channels 45 262 adapted to be brought coincident with the respective openings 231 and 232 of the cover plate 230 of the casting 220. The solid portions of the slide valves 260 and 261 between openings serve to cut off the flow of 50 265 confection to the openings 231 and 232 of the cover-plate 230, when the slide valves are shifted.

55 The slide valves 260 and 261 are operated by mechanism next to be described. To the outer ends of the valves 260 and 261 are pivotally connected the yoke-shaped ends of the rocking arms 265 and 266 fixed to the upper ends of vertical rods 267 and 268 (see Figs. 2, 4, and 8), the lower ends of which rods 60 265 pass through holes formed in the ends of the

bolts 269 and 270 that project inwardly from one of the side frames of the machine (see Figs. 2 and 4). The lower ends of the rods 267 and 268 have fixed thereto, respectively, the rock arms 271 and 272 that carry 70 rollers 271^a—272^a which project into peripheral grooves of the cam wheels 273 and 274 (see Fig. 4), mounted respectively on the shafts 146 and 151.

75 From the foregoing description it will be seen that when a row of cakes is moved by the supplemental movable step 10^a (see Fig. 2) to a position beneath the row of nipples 241 (see Figs. 6, 8 and 8^a) the carrier belt, to which a step by step movement is imparted, will temporarily stop and, at such time, the sections of the table and the carrier belt 46 thereon will be raised (by the mechanism hereinbefore described) to lift the row of cakes into close proximity to the lower ends 80 of the nipples 241. As a row of cakes is thus lifted toward the nipples 241, the spaces 106 of the cylindrical plunger carriers 101 and 102 are brought opposite the discharge passages or spaces 234 and 236, 85 as shown in Fig. 6. At such time, the plungers are in the raised position shown in Fig. 6, and the mutilated gear wheels that drive the cylindrical plunger carriers 101 and 102 allow these plunger carriers to remain at 90 rest, while, through the mechanism above described, the plungers 120 and 121 move downward and respectively force the marshmallow and chocolate from the spaces 106 toward the nipples 241. The marshmallow 95 passes through the space 234 and through the delivery pipes 240 down on to the cakes, while, at the same time, the chocolate is forced through the space 236 and openings 232 into the annular spaces that surround 100 the delivery pipes 240. Hence, as the marshmallow passes to the cakes, it is surrounded with a coating of chocolate. As soon as the plungers 122 and 123 have completed their strokes, the mutilated gear 105 wheels will again be driven to rotate the cylindrical plunger carriers 101 and 102 and, at the same time, by the mechanism above described, the slide valves 260 and 261 will 110 be shifted by the rock arms 265 and 266 and the mechanism above described, so as to cut off the flow of marshmallow and of chocolate through the openings 231 and 232, respectively, in the cover-plate 230 (see Fig. 6). The rotation of the cylindrical plunger carriers 101 and 102 will close the passages 115 234 and 236 at the same time that the valves 260 and 261 cut off the flow of marshmallow and of chocolate through the openings 231 and 232. At the same time also the valve 120 shifters 247, actuated by the rock shaft 248 (see Figs. 6 and 8) and mechanism above described, will cause the tubular valves 244 to descend and promptly check the flow of 125 chocolate through the nipples. At the time 130

the flow of chocolate through the nipples is thus checked, the carrier belt 46 will be lowered to move the row of cakes away from the nipples, and this downward movement 5 of the belt will break off portions of the marshmallow that have adhered to the cakes and allow such portions to be completely covered by the chocolate passing through the annular spaces in the nipples 241. It 10 will be understood, of course, that the various parts of the machine above described will be so accurately adjusted and their movements so relatively timed that, as each row of cakes is brought beneath the nipples 15 241 it will have the proper amount of confection delivered thereto before the carrier belt advances to deliver the next succeeding row of cakes to receive its deposit of confection.

20 While I have described my depositing mechanism as delivering to the cakes marshmallow coated with chocolate, it will be understood that other kinds of confection may be used. Thus, for example, instead of 25 chocolate, a coating of "icing" may be used, and this is frequently advantageous, as such icing quickly hardens and enables the cakes to be readily handled and packed. When it is desired to add a further confection, such 30 as jelly, to the confection deposited upon the cakes by the devices hereinbefore set forth, I employ the mechanism next to be described, reference being had more particularly to 35 Figs. 1 to 4 and 9 to 12 of the drawings. At the rear of the receptacles 103 and 104 for containing the marshmallow and the chocolate, is mounted a supplemental receptacle for containing jelly or like confection, small 40 portions of which will be deposited upon, or embedded in, the confection already placed upon the cakes. This jelly receptacle 300 is conveniently held in place by means of brackets which enable the adjustment of the jelly receptacle to be effected. As shown, 45 brackets 301 are attached to the ends of the receptacle 104, these brackets being formed with outwardly projecting flanged portions 302 having lugs 303 through which pass adjusting bolts 304 that engage the end members 305 of the frame or bracket 306 having arms 307 attached to the upper end of the jelly receptacle 300. The frame or bracket 306 has flanges 308 provided with threaded 50 openings to receive adjusting screws 309 that bear upon the top of the brackets 301 (see Figs. 1, 2 and 3). Bolts 310 (see Fig. 5) passing through slots in the outer flanges 302 of the brackets 301 and through the ends 55 of the bracket 306, serve to securely hold the jelly receptacle 300 in place when its proper position has been accurately determined. The arms 307 of the bracket or frame 306 that engage with the upper part of the jelly receptacle 300 are slotted, as shown (see 60 Figs. 1, 3 and 10), to receive bolts 308a whereby these arms are adjustably connected to the jelly receptacle. As shown, the lower portion of the jelly receptacle 300 has bolted thereto as at 320a a bottom casting 320 (see Fig. 10) through the upper wall of which is 65 formed a series of openings to receive the plungers 321 to be presently described, and in the lower portion of this casting 320 is formed a corresponding series of openings 322 through which the jelly will be ejected by the plungers 321. Preferably, each of the openings 322 is fitted with a tubular pointed nipple 323 that depends therefrom, as shown in Figs. 9 and 10. The plungers 321 are carried by a plunger bar 325 that extends from 70 end to end of the jelly receptacle 300 above the bottom casting 320. This casting 320 is preferably formed with upright portions 327 having slots therein through which the ends of the plunger bar 325 pass. The plungers 75 321 are adjustably connected to the plunger bar (as shown in Figs. 9 and 10), so that the extent of their movement may be accurately determined. The ends of the plunger bar 325 are engaged by the yoke-shaped ends 80 of the rock arms 330 that are mounted upon the ends of shaft 332 journaled in lugs 333 projecting from the jelly receptacle 300. One of these rock arms 330 is formed with a long slot 335 (see Figs. 1, 3 and 10) through 85 which passes a bolt 336 having a nut upon its inner end whereby the bolt can be adjusted to any position along the slot (see Fig. 12). As shown, this bolt 336 is formed with a shoulder 337 that bears against the 90 outer wall of the slot. Upon the bolt 336 is mounted the sleeve 340 at the upper end of the rod 341. This rod 341 is preferably formed in sections adjustably connected by a turn-buckle 342 (see Fig. 3) and the lower 95 end of this rod is pivotally connected to the upper member of an elbow lever 343 that is mounted upon the outer end of the shaft 344 that passes through the side frames of the machine (see Figs. 2 and 4). The lower 100 member of the elbow lever 343 has pivotally connected thereto one end of a pitman rod 345, the opposite end of which is pivoted to an arm 346 (see Fig. 3) that is pivotally 105 mounted upon a stud 347 projecting outwardly from one side of the main frame of the machine. This arm 346 carries a friction roller 348 mounted on a pivot 348a adapted to bear against the periphery of a cam-wheel 349 that is mounted upon the 110 outer end of the cam shaft 29. The cam wheel 349 is formed with segmental slots 350 through which pass adjusting bolts 351 that 115 adjustably connect the cam wheel to a disk or plate 352 (see Fig. 4) that is fixed to the 120 cam shaft 29. Upon the pitman rod 345 is placed a coil spring 354 that bears against a plate 355 that engages a yoke-shaped lug (see Fig. 3) that projects outwardly from the main frame of the machine, the opposite 125 130

end of this coil spring bearing against the coupling at the upper end of the rod. The spring 354 serves to hold the friction roller 348 of the rocking arm 346 in engagement 5 with the cam wheel 349.

A row of cakes will be brought beneath the row of discharge nipples 323 under the jelly receptacle 300 at the same time that a row of cakes is brought beneath the nipples 10 241 through which marshmallow and chocolate will be discharged, as hereinbefore described, and, when a row of cakes is centrally beneath the nipples 323, the carrier belt 46 will be arrested and will be lifted 15 by the table sections, as hereinbefore described. As the carrier belt is thus lifted, the row of cakes will be raised until the previously deposited marshmallow and chocolate thereon touches the lower ends of the 20 nipples 323 through which jelly will be discharged; or, if it is desired to embed the jelly within the marshmallow, the nipples 323 may be given such lengths as to project into the marshmallow when the cakes are 25 raised. As the carrier belt 46 is thus raised, the plungers 321 are caused to descend and each plunger will eject from the nipples 323 beneath it a small deposit of 30 jelly.

35 The jelly or like confection usually deposited upon the marshmallow is ordinarily of such consistency that no cut-off valve is necessary to check its flow when the plungers are returned to the raised position shown in Figs. 9 and 10 of the drawings. After the jelly has thus been deposited upon or into the marshmallow and the chocolate coating, the carrier belt 46 will descend and, by the mechanism hereinbefore described, 40 will advance the cakes toward the discharge end of the machine, bringing a fresh row of cakes beneath the nipples 323.

Having thus described my invention, what I claim as new and desire to secure by Letters Patent, is:—

45 1. In a machine of the character described, the combination with a depositing mechanism, of means for feeding cakes or the like to said depositing mechanism comprising sets of alternately arranged steps having a relative reciprocating movement sufficient to project the cakes or the like from one step to the next at each throw, the front edges of said steps being inclined, and means for relatively shifting said steps.

50 2. In a machine of the character described, the combination with a depositing mechanism, of means for feeding cakes or the like to said depositing mechanism comprising sets of alternately arranged steps having a relative reciprocating movement sufficient to project the cakes or the like from one step to the next at each throw, the movable steps being provided with plates

extending over their front edges, and means 65 for relatively shifting said feeding steps.

3. In a machine of the character described, the combination with carrier mechanism, of a depositing mechanism comprising a receptacle for containing the material 70 to be deposited and means for delivering the material from said receptacle comprising a revoluble plunger carrier having a chamber extending longitudinally thereof and diametrically therethrough, a plunger arranged 75 within and partially filling the chamber of said plunger carrier and movable radially from side to side thereof, means for revolving said plunger carrier, and means for reciprocating said plunger at right angles to 80 the axis of the plunger carrier to discharge material on opposite sides of the chamber of said carrier.

4. In a machine of the character described, 85 the combination with a carrier mechanism, of a depositing mechanism comprising a receptacle for containing the material to be deposited, and means for delivering the material from said receptacle comprising a revoluble plunger carrier extending transversely beneath said receptacle, said plunger carrier being formed of chambered sections connected together, a reciprocating plunger partially filling the chamber of said plunger carrier and mounted 90 within and extending longitudinally of said plunger carrier and movable radially therethrough from side to side thereof, means for revolving said plunger carrier, and means for reciprocating said plunger. 95

5. In a machine of the character described, 100 the combination with carrier mechanism, of a depositing mechanism comprising a receptacle containing the material to be deposited, and means for delivering the material from said receptacle comprising a revoluble plunger carrier having a chamber extending longitudinally thereof and diametrically therethrough, a casing wherein 105 said plunger carrier is revolvably mounted, said casing having a discharge passage therein, a plunger arranged within and partially filling the chamber of said plunger carrier and movable radially from side to side thereof, means for intermittently revolving said plunger carrier to bring the operating faces of the plunger successively opposite the discharge passage of the casing, and means for reciprocating the 110 plunger while the plunger carrier is at rest. 115

6. In a machine of the character described, 120 the combination with carrier mechanism, of a depositing mechanism comprising a receptacle for containing the material to be deposited, and means for delivering the material from the receptacle comprising a revoluble plunger carrier arranged beneath 125 said receptacle and having a chamber ex-

- tending longitudinally thereof and diametrically therethrough, a reciprocating plunger mounted within the chamber of the plunger carrier and partially filling said chamber, 5 a bar extending through said plunger carrier and connected to said plunger, and means connected to said bar for reciprocating said plunger radially of and from side to side of said plunger carrier.
- 10 7. In a machine of the character described, the combination with carrier mechanism, of depositing mechanism comprising a receptacle containing material to be deposited, and means for delivering material from said 15 receptacle comprising a revoluble chambered plunger carrier beneath said receptacle, said plunger carrier being open at different points of its periphery, a casing or support wherein said plunger carrier is revolubly mounted, 20 said casing or support communicating at one point with said receptacle and being provided at another point with a plurality of contracted discharge passages, a series of discharge nipples communicating with said 25 passages and arranged above said carrier mechanism, plunger mechanism mounted in and revoluble with said plunger carrier, means for intermittently revolving said plunger carrier to bring the plunger mechanism simultaneously opposite said receptacle and said discharge passage, and means 30 for actuating said plunger mechanism to simultaneously draw in a charge of material from the receptacle and to force material 35 through said contracted discharge passages while the plunger carrier is at rest.
8. In a machine of the character described, the combination with carrier mechanism, of depositing mechanism comprising a receptacle containing material to be deposited, and means for delivering material from said receptacle comprising a revoluble, cylindrical, chambered plunger carrier beneath said receptacle, said plunger carrier being open at 40 different points of its periphery, a casing or support inclosing said plunger carrier and wherein said plunger carrier is revolubly mounted, said casing or support communicating at one point with said receptacle being 45 provided at another point with a plurality of contracted discharge passages, plunger mechanism mounted in and revoluble with said plunger carrier, means for intermittently revolving said plunger carrier to bring the plunger mechanism simultaneously opposite said receptacle and said discharge passage, and means outside said plunger carrier for actuating said plunger mechanism to simultaneously draw in a charge of material 50 from the receptacle and to force material through said contracted discharge passages while the plunger carrier is at rest and a valve movable transversely across said discharge passages to cut off the flow of material 55 therethrough.
9. In a machine of the character described, the combination with carrier mechanism, of a depositing mechanism comprising a receptacle for containing the material to be deposited, means for delivering the material from said receptacle comprising a revoluble plunger carrier beneath said receptacle, a chambered support wherein said plunger carrier is mounted, said support having a discharge passage leading therefrom, a reciprocating plunger within said plunger carrier and movable radially thereof, mechanism for actuating said plunger carrier and said plunger, a discharge nipple communicating with the discharge passage of said plunger carrier support, a slide valve arranged above said discharge nipple for controlling the flow of material through said passage, and mechanism for reciprocating said slide valve. 75
10. In a machine of the character described, the combination with carrier mechanism, of a depositing mechanism comprising a plurality of receptacles for containing different materials to be deposited, and means for delivering said materials from said receptacles comprising a plurality of discharge nipples arranged above said carrier mechanism, a plurality of discharge pipes communicating with one of said receptacles and located within said nipples, said discharge pipes being of smaller diameter than said nipples and the space between said discharge pipes and said nipples being in communication with the other of said receptacles, a revoluble chambered plunger carrier beneath each of said receptacles, said plunger carrier being open at different points of its periphery, a casing or support wherein said plunger carriers are revolubly mounted, and plunger mechanism mounted in and revoluble with each of said plunger carriers and serving to draw in the materials from said receptacles and force them through said pipes and nipples, and individual valves transversely shiftable across the passages between said plunger mechanism and said pipes and nipples for cutting off the flow of materials through the latter. 90
11. In a machine of the character described, the combination with carrier mechanism, of depositing mechanism comprising a receptacle containing material to be deposited, and means for delivering material from said receptacle comprising a revoluble, chambered plunger carrier beneath said receptacle, said plunger carrier being open at different points of its periphery, a casing or support wherein said plunger carrier is revolubly mounted, said casing or support communicating at one point with said receptacle and being provided at another point with a discharge pipe, plunger mechanism mounted in and revoluble with said plunger carrier, gear operated pitmen outside 95
- 100
- 105
- 110
- 115

and at opposite ends of said plunger carrier for actuating said plunger mechanism, and mutilated gear mechanism connected with said plunger carrier for intermittently actuating the same.

12. In a machine of the character described, the combination with carrier mechanism, of a depositing mechanism comprising a plurality of receptacles for containing different materials to be deposited, and means for delivering said materials from said receptacles comprising a discharge nipple, a discharge pipe of smaller diameter than said nipple and located therein, said discharge pipe being connected with one of said receptacles and the space between the discharge pipe and the nipple being connected with the other of said receptacles, a tubular valve encircling said discharge pipe, and means for automatically shifting said valve to cut off the flow of material from the space between the discharge pipe and the nipple.

13. In a machine of the character described, the combination with carrier mechanism, of a depositing mechanism comprising a plurality of receptacles for containing different materials to be deposited, and means for delivering said materials from said receptacles comprising a discharge nipple having an inwardly projecting flange, a discharge pipe of smaller diameter than said nipple and located therein, said discharge pipe being connected with one of said receptacles and the space between the discharge pipe and the nipple being connected with the other of said receptacles, a valve encircling said discharge pipe, and means for reciprocating said valve.

14. In a machine of the character described, the combination with carrier mechanism, of depositing mechanism comprising a plurality of receptacles for containing materials to be deposited, means for delivering the materials from said receptacles comprising a support having two cylindrical chambers, two revolute plunger carriers arranged side by side within said support, said support having discharge passages leading from the chambers for said plunger carriers, side valve mechanism for controlling the flow through said discharge passages, a chambered part or casting located beneath said support and removably connected therewith, the top of said chambered part having openings therein and said top extending beneath and forming the lower wall of said discharge passages, a discharge pipe leading through said chambered part or casting, and a nipple at the bottom of said chambered part or casting and surrounding said discharge pipe.

15. In a machine of the character described, the combination with carrier mechanism, of a depositing mechanism comprising

a plurality of receptacles for containing the material to be deposited, a support arranged beneath said receptacles and having two cylindrical openings therein extending from end to end of said support, said support being provided with discharge openings leading from said cylindrical openings, a chambered part or casting detachably connected centrally beneath said support and having a top serving as the lower wall of said discharge passages, a discharge pipe leading through said chambered part or casting, a nipple depending from the lower portion of said part or casting and surrounding the lower edge of said discharge pipe, slide valves mounted within said support immediately above said part or casting for controlling the flow of materials through said discharge passages, means for operating said slide valves, plunger carriers revolutely mounted within said support, plungers mounted in said revolute plunger carriers, and means for actuating said plunger carriers and plungers.

16. In a machine of the character described, the combination with carrier mechanism, of a depositing mechanism comprising a plurality of receptacles for containing materials to be deposited, means for delivering the materials from said receptacles comprising a chambered support, two revolute plunger carriers arranged side by side within said support, said support having discharge passages leading from said plunger carriers, slide valve mechanism for controlling the flow through said discharge passages, a chambered part or casting located beneath said support and removably connected therewith, a discharge pipe leading through said chambered part or casting, a nipple at the bottom of said chambered part or casting and surrounding said discharge pipe, and valve mechanism within said chambered part or casting for arresting at the discharge nipple the flow of material from the space between the nipple and the discharge pipe.

17. In a machine of the character described, the combination with carrier mechanism, of a depositing mechanism comprising means for depositing marshmallow or the like upon cakes or like articles supported on the carrier mechanism, and a supplemental depositing mechanism comprising a receptacle for jelly or the like, a series of nipples beneath said jelly receptacle, plunger mechanism for ejecting material through said nipples, and means for actuating said plunger mechanism, said supplemental depositing mechanism being adjustably mounted in horizontal direction at the discharge side of said first mentioned depositing mechanism.

18. In a machine of the character described, the combination with carrier mecha-

nism, of a depositing mechanism comprising means for depositing marshmallow or the like upon cakes or like articles supported on the carrier, said depositing mechanism comprising a plunger for ejecting the marshmallow or the like, supplemental depositing mechanism comprising a receptacle for jelly or the like and being adjustably mounted in horizontal direction with respect to 10 said marshmallow depositing mechanism, a

series of nipples beneath said jelly receptacle, a series of plungers for ejecting material through said nipples, and means for actuating said plungers in timed relation with the plungers for depositing marshmallow or the 15 like.

FREDERICK WESTERMAN.
